REFRIGERATION

Randolph N. Stenerson, East Syracuse, N.Y., assignor to Carrier Corporation, Syracuse, N.Y., a corporation of Delaware

Filed Apr. 25, 1960, Ser. No. 24,313
3 Claims. (Cl. 62—304)

This invention relates to a refrigerated article and a method of refrigeration. More particularly, this invention relates to the refrigeration of metal bodies without the use of conventional compressors and heat exchange devices by the improved utilization of evaporative cooling.

The refrigeration of a small article is conventionally accomplished by constructing a mechanical refrigeration system, a heat absorbing element of which is placed in heat exchange relation with the article to be refrigerated. Such systems are generally satisfactory and economically feasible only where weight and space considerations permit their use. Frequently, however, these considerations militate against the use of a conventional mechanical refrigeration system especially where the body to be cooled is small in size or the additional space available for the refrigeration apparatus is limited.

In addition, a conventional mechanical refrigeration system is required to have a mechanical or electrical power input. However, situations are encountered where a convenient power source is either lacking or the use of a cooling system requiring substantial apparatus in connection with it or a substantial power input to operate it also militates against the feasibility of utilizing conventional refrigeration. The use of a mechanical refrigeration system may also be impractical because the smallest system which it is feasible to make frequently has a minimum capacity far in excess of the cooling requirement of the body to be cooled. This is particularly true in the case of cooling small metal objects, such as the substage of a biological microscope or the jumper of a thermoelectric element, where the cooling required may be small or the requirement for cooling intermittent rendering the use of conventional refrigeration uneconomical and impractical.

Furthermore, practical utilization of typical external mechanical refrigeration systems to cool such bodies frequently requires substantial and expensive design changes in the construction of the body itself for the purpose of accommodating heat exchange tubes. Alternatively, a cooled heat exchange medium may be flowed over the surface of the body but under some circumstances this is undesirable and frequently the heat transfer which is obtainable by this method is poor. Also, it may be very difficult to obtain satisfactory refrigeration by conventional means of an irregularly shaped or inaccessibly placed body because of the necessity of uniformly supplying heat exchange medium to an irregular surface of the body. Furthermore, if the body need be portable, either the entire refrigeration system must be carried with it or long flexible conduits would have to be attached to it.

It is well known that a substantial amount of heat is required to vaporize a liquid. This principle, which is referred to as evaporative cooling, is often used to remove heat from a body by flooding it with a liquid which is then permitted to evaporate or boil from the surface of the body, and therefore, cool it. Evaporative cooling offers the advantage that the heat transfer capacity is very great because a relatively large quantity of heat must be absorbed from a body to vaporize a liquid on its surface. In addition, if the ambient conditions are such that the liquid on the surface of a body boils, then the rate of heat transfer can be very great. Furthermore, a fairly con-

2

stant temperature may be maintained by means of evaporative cooling because the rate liquid from the surface of a body is evaporated will depend on the heat added to the body. However, this principle has serious drawbacks in practical application because of the necessity of continuously replenishing the liquid supply. In addition, if any substantial quantity of liquid exists on the surface of the body, the thickness of the liquid itself tends to insulate the body and retain the heat therein. On the other hand, if the film of liquid on the body surface is thin so that the body tends to reach the temperature of the film, only a small amount of cooling may be obtained before it is necessary to again replenish the supply of liquid on the surface of the body.

Consequently, prior art heat exchangers which employed evaporative cooling frequently used sprays or other continuously operating means to supply a thin film of liquid for evaporation from the surface of the heat exchanger. This technique for maintaining a thin film requires the use of the spray system, a collecting sump and pumps which undesirably increase the cost, size and weight of the system. Furthermore, for many applications such as refrigeration of small portable metal bodies, the installation of a spray system to provide evaporative cooling of the body would be prohibitive. In addition, a spray system may pose the problem of removing entrained liquid from the ambient atmosphere surrounding the body which is to be cooled. Furthermore, since some of the liquid sprayed into the ambient atmosphere is always evaporated, the capacity of the atmosphere to evaporate liquid from the body is correspondingly reduced. If the surrounding atmosphere is substantially saturated with liquid by the spray system, little, if any, evaporation can occur from the surface of the body and it will be impossible to reduce the temperature of the body below its ambient temperature by the evaporative cooling technique because each grain of liquid absorbed by the ambient atmosphere reduces the capacity of the atmosphere to evaporate liquid from the surface of the body by the same amount.

Another serious problem in the use of evaporative cooling of a body arises because of the difficulty in maintaining a uniform distribution of liquid on the surface which is to be cooled. Since any liquid has a certain surface tension, the liquid even when applied to the surface of a body in the form of a finely divided spray tends to coalesce into droplets on the surface of the body. Where the liquid has formed a droplet on the surface of the body, the thickness of the liquid at that point is very great and heat transfer is inhibited. On the other hand, the regions between the liquid droplets on the surface of the body may be substantially dry and consequently, no evaporative cooling will take place in these regions. It is, consequently, difficult but highly desirable to maintain a uniformly thin film of liquid over the entire surface of the body to be evaporatively cooled for efficient heat transfer.

Accordingly, it is an object of this invention to provide an improved metal body which is especially adapted to being evaporatively cooled.

It is a further object of this invention to provide an improved method for evaporatively cooling a metal body. These and other objects of this invention, which will become apparent by reference to the attached drawing and specification, are achieved by forming a porous metal body having a large number of minute internal pores of capillary size and a large number of interstices in a surface of the body in communication with the internal pores by compacting a metal powder into the desired shape of the body. The metal body is then impregnated with the volatile liquid by contacting a surface having interstices therein with the liquid, thereby filling the pores with the

liquid through capillary action. The body is then located in a suitable ambient atmosphere which is unsaturated with respect to the vapor of the liquid. Under these conditions, a thin film of the liquid is continuously supplied to the surface of the body from its pores through the surface interstices by capillary action. The thin film of liquid continuously evaporates by absorbing heat from the body and since the body is metallic in composition, heat is conducted from the interior of the body to its surface and the body itself may be effectively cooled by this method for a substantial period of time.

The method and construction of a preferred embodiment of this invention will be apparent from the following specification having reference to the attached drawing wherein:

FIGURE 1 is an elevational view, partly cut away, of a body made in accordance with this invention;

FIGURE 2 is a cross-sectional view illustrating the compacting step of the described method; and

FIGURE 3 is a cross-sectional view illustrating the impregnating step.

Referring to the drawing, there is shown a metal article or body 10 which is adapted to be refrigerated. Body 10 is characterized by having a large number of internal communicating pores or voids throughout at least a portion of its interior. At least one surface 16 of the body, these pores form interstices. The pores and interstices are preferably of minute or capillary size so that a liquid in contact with the surface is drawn into the interior of the body by capillary action. If the use to which the body is to be put permits it, it is desirable that all of its surfaces have interstices therein, but it will be appreciated that if only one surface need be cooled or if only one surface will be exposed to ambient atmosphere, that this surface alone may contain interstices. The voids should preferably occupy a substantial portion of the volume of the body for a reason which will become apparent.

Body 10 is conveniently made by compacting powdered metal into a relatively homogeneous mass having a large number of minute internal pores. For effective cooling of the body, it is desirable that the metal powder be copper, aluminum or some other metal having relatively high thermal conductivity. It will be appreciated that various electrical and chemical processes are feasible for manufacture of metal powders; for example, powder 14 may be made by electrolytic decomposition of a metal salt. Such processes are well known in the metallurgical arts and need not further be described. The process which is used to form the metal powder will to some extent determine the nature of the powder. For example, ball milling may produce chunky particles which may be in the form of generally spherical balls. On the other hand, electrolytic deposition may form dendritic crystals of the metal which are especially desirable for the purposes of this invention. Dendritic crystals characteristically are long needle or "pine tree" shaped particles which compact into a relatively solid mass upon the application of reasonably low pressures. A body formed by compacting dendritic metal crystals is highly desirable for the purposes of this invention because of the very large number of minute internal voids or pores which are characteristic of such compacts. Such compacts readily absorb liquids due to capillary action and at the same time hold substantial quantities of the liquid within the compacted metal body. However, other forms of crystal-compacted metal powders may be used to make a body in accordance with this invention.

Mold 11 is formed with an open cavity having the desired shape of the finished article and may be inserted in the base of a hydraulic press 13. It will be understood that the shape of article 10 may be irregular if desired. A ram 12 having an appropriately shaped face is depressed by the action of a hydraulic piston into the cavity of mold 11 for the purpose of applying pressure to the

powder 14 therein. It is desirable to use no more pressure in compacting powder 14 than is necessary to provide a body of the desired rigidity so as not to seal off or eliminate the pores within the body by overcompacting the metal powder. It will be understood that the precise pressure to be applied will depend upon the crystalline nature of the powder being compacted and upon the material of which the powder is made. By way of example, dendritic crystals of electrolytically deposited copper may be compacted into a suitable rigid body by a pressure of approximately 800 p.s.i.

It will also be understood that other processes than the one described may be used for compacting powder 14. For example, powder 14 may be sintered to form a relatively rigid body 10. However, care must be exercised to insure that the process used is controlled so that compacting or fusing of the particles of metal powder is stopped before the internal voids in the material are eliminated or sealed, the crystals fusing or coalescing so that they no longer communicate with a surface of the body. Unless the voids communicate with the surface of body 10, the body will be unable to hold sufficient liquid to be useful for the purposes of this invention.

After body 10 has been properly compacted so that the minute voids are homogeneously distributed throughout at least a portion of its interior and in communication with interstices in at least one of its surfaces, the body is impregnated with a volatile refrigerant liquid. The particular liquid which is selected by impregnation into body 10 will be determined by the ambient atmosphere which will surround the body during its use. The liquid should have sufficient vapor pressure so that it evaporates or boils rapidly enough to remove the desired amount of heat from the body. On the other hand, the refrigerant vapor pressure should not be so high as to entirely boil or evaporate from the body too quickly to maintain the desired temperature for the desired period of time. Also the refrigerant should be one which is not present to such an extent in the ambient atmosphere in which the body is to be placed to inhibit a satisfactory rate of vaporization from the surface of the body. For example, if the body is impregnated with "Freon 11" (trichloromonofluoromethane), the body would not be suitable for use in a saturated ambient atmosphere of Freon 11, but would be generally satisfactory for use in normal room air containing little, if any, Freon 11.

Any suitable refrigerant liquid including water having the desired evaporation or boiling characteristics may, of course, be used to impregnate the body and the liquids suitable for this use are not limited to those which are customarily referred to as "refrigerants" in a mechanical system. Precautions must be taken, however, to insure that the particular refrigerant liquid employed does not carry in it sufficient impurities to clog the pores or interstices of the body and the liquid must be noncorrosive when used with the particular metal of which the body is formed.

Impregnation of the body is conveniently performed by taking advantage of the minute size of the pores therein and utilizing them to attract the refrigerant by capillary action. FIGURE 3 shows a vessel 15 partially filled with liquid 17 into which body 10 has been placed. By this means, surface 16 of body 10 have interstices therein in communication with the internal pores of the body, is placed in contact with liquid 17 and, as shown, may be spaced from the bottom of vessel 15 during this step. Consequently, liquid 17 is drawn into the pores of body 10 where it is held for a period of time after the body is removed from vessel 15.

Body 10 is then placed in ambient atmosphere which is nonsaturated with respect to the vapor of liquid 17 with which it has been impregnated. As the thin film of liquid which will adhere to surface 16 is vaporized therefrom, additional liquid will be fed to the surface of the body by capillary action from the internal pores of the body

through the surface interstices to replenish the surface film. Consequently, the vaporization process may continue for several hours depending on the capacity of the internal pores or voids and the ambient conditions before the supply of liquid in the pores of body 10 is exhausted. When the supply of liquid within the pores is exhausted the body may be reimpregnated as described above or a quantity of liquid may be continuously supplied for absorption by the body if desired by a cyclic or a wicking process.

It will be noted that at no time during the vaporization process is there an excess of accumulated liquid on the surface of the body and consequently, the heat transfer advantages of an extremely thin film of evaporating or boiling liquid are substantially realized. However, this advantage has been secured without substantial modification in the shape of the body and without the need for external apparatus.

Numerous applications of this invention will occur to those skilled in the art. For example, by this means it is possible to maintain a relatively efficient heat transfer surface without the inclusion of external fins or other heat exchange apparatus. Consequently, body 10 may comprise the jumper of a thermoelectric device or other heat exchange member because the metal material, such as copper, of which it is composed is both a good thermal and electrical conductor. Another application for a refrigerated body of this type herein described is in maintaining a temperature of a specimen which is under examination in a biological microscope where the heat absorbed by the specimen from the illumination source may tend to decompose the specimen. By making the substage of the microscope of a powdered refrigerant impregnated heat conducting metal and resting the specimen thereon, the refrigerant will evaporate slowly from the body of the substage maintaining the specimen temperature relatively constant during the examination. A still further application of this invention lies in insulating the working end of a hand tool from body heat by inserting a porous refrigerant impregnated heat conducting section between the handle and end of the tool. As the refrigerant vaporizes from the porous section, it will carry away body heat which has been conducted to it through the tool handle. Various other applications such as those involving heat exchangers within the scope of this invention will occur to those skilled in the art.

While I have described a preferred embodiment of this invention, it will be understood that the invention is not limited thereto since it may be otherwise embodied within the scope of the following claims.

I claim:

1. A metal structure adapted to be refrigerated comprising a relatively rigid body of compacted dendritic metal powder of a relatively good heat conducting mate-

rial, said body having a large number of specially constructed, minute, internal voids of capillary size occupying a substantial fraction of the total volume of said body, said internal voids being in communication with an exterior surface of said body through a large number of surface interstices therein, and a volatile liquid contained within said voids so that exposure of said surface of said body to an ambient atmosphere which is nonsaturated with respect to vapor of said liquid produces evaporative cooling of said surface and heat may be conducted from the interior of said metal body and dissipated therefrom for a substantial period of time before the supply of said liquid within said pores is exhausted.

2. A structure as defined in claim 1 wherein said body comprises compacted dendritic copper powder.

3. In a method of making a refrigerated metal body adapted to be cooled by evaporation of a liquid from a large number of surface interstices in communication with a large number of specially defined, minute, internal voids in said body when said body is exposed to an ambient atmosphere which is nonsaturated with respect to the vapor of said liquid, the steps consisting of charging a mold of a predetermined desired shape with a quantity of dendritic particles of a relatively good heat conducting metal material, applying a pressure to said metal particles while in said mold of a magnitude sufficient to compact said particles into a rigid internally porous body having a large number of surface interstices in communication with a large number of specially formed, minute, internal pores resulting from the compacting of said dendritic particles, and impregnating said porous body with a volatile liquid by contacting a surface thereof having interstices therein with said volatile liquid to substantially fill the pores thereof with said liquid by capillary action so that when said surface is exposed to an ambient atmosphere which is nonsaturated with respect to the vapor of said liquid, heat is removed from said body and said body is thereby refrigerated by vaporization of said liquid from said surface thereof and the supply of liquid to said surface is replenished by capillary movement of liquid from said pores to said surface through said interstices, the heat conducting characteristics of said metal body serving to facilitate removal of heat from said body by vaporization at its surface.
